A. C. KEPPLER

SIGNAL ARM ACTUATING DEVICE

Filed Sept. 17, 1921

UNITED STATES PATENT OFFICE.

ARTHUR C. KEPPLER, OF SOUTH BEND, INDIANA.

SIGNAL-ARM-ACTUATING DEVICE.

Application filed September 17, 1921. Serial No. 501,308.

To all whom it may concern:

Be it known that I, ARTHUR C. KEPPLER, a citizen of the United States, residing at South Bend, in the county of St. Joseph and State of Indiana, have invented certain new and useful Improvements in Signal-Arm-Actuating Devices, of which the following is a specification, reference being had to the accompanying drawings.

- 10 It is the purpose of the present invention to provide an actuating device of this character particularly adapted for use in connection with the shiftable indicia bearing signal elements described, claimed and illustrated 15 in the copending application, Serial No. 554,092, filed March 21, 1921, whereby upon operating the signal or semaphore arm in said application, the indicia bearing elements are shifted automatically.
- 20 In the present invention the arm is normally disposed in a vertical position, depending from the casing of the actuating device, it being the aim to move the arm to an outwardly and downwardly inclined position 25 to indicate left turn, a horizontal outwardly disposed position to indicate stop, and an upwardly inclined position to indicate right turn, therefore it is another purpose of the present invention to provide an 30 actuating device for positioning the signal or semaphore arm in any one of these three different positions, and at the same time automatically actuate the indicia bearing elements, and also lighting an electric bulb, 35 which reflects through the indicia bearing elements to permit the indicia to be visible after dark.

A still further purpose is the provision of an actuating device, wherein a single handle 40 operates to move a piston, which in turn operates the arm through the medium of connecting means therewith, and also operates a contact collar, which closes the electric lamp circuit. It is obvious that when the 45 semaphore or signal arm is tilted to any one of these three different positions, for the purpose of indicating to the chauffeur of a following vehicle, the movements of the vehicle in front, the indicia bearing elements 50 are pulled in front of the openings in the arm, due to connections between the elements and the casing of the actuating device.

While the design and construction at present illustrated and set forth are deemed 55 preferable, it is obvious that as a result of a reduction of the invention to a more prac-

tical form for commercial purposes, the invention may be susceptible of changes, and the right to these changes is claimed, provided they are comprehended within the 60 scope of what is claimed.

The invention comprises further features and combination of parts, as will be herein-after set forth, shown in the drawings and 65 claimed.

In the drawings:—

Figure 1 is a view in elevation showing the improved semaphore or signal arm actuating device constructed in accordance 70 with the invention;

Figure 2 is a longitudinal sectional view through the actuating device showing the connections between the arm and the piston within the casing;

Figure 3 is a longitudinal sectional view 75 through the semaphore or signal arm showing the indicia bearing elements;

Figure 4 is a sectional view on line 4—4 of Figure 3;

Figure 5 is an enlarged detail view of the 80 rear end of the casing of the actuating device showing the rotatable collar 17 and the notches 23;

Figure 6 is a sectional view on line 6—6 of Figure 2; and

Figure 7 is a detail view of the bracket 2 and the manner of connection between it and the casing of the actuating device.

Referring to the drawings, 1 designates the casing of the actuating device, which is 90 mounted upon a bracket 2, to be suitably connected as at 3 to a portion of the body of the motor vehicle. This casing is bifurcated at one end, and pivotally mounted in the sides 3^a caused to be formed by a bifurcation 4 is a reduced lug 5 of the casing 6 of the signal or semaphore arm. The pivot 7 for the lug 5 is located adjacent the end portions of the sides of the bifurcation. The lug 5 of the signal or semaphore arm is also 95 provided with a bifurcation 8, in which a link 9 is pivotally mounted upon a pin 10. A lever 11 is pivotally mounted at 12 in the bifurcation 4 and is provided with spaced arms 13, between the ends of which the link 100 105 9 is pivoted as at 14.

The casing 1 is preferably rectangular in contour, though not necessarily, and is hollow, and has its end opposite the bifurcation 4 reduced to cylindrical form. This reduced 110 cylindrical portion 15 of said casing has a segmental slot 16, and rotatably fitted on the

reduced portion 15 is a collar 17. The interior of the casing 1 is cylindrical and rotatable therein is a sleeve 18. A handle 19 engages through an opening 20 in the collar 17 and through said segmental slot 16, and is threaded at 21 in the sleeve 18, so that when the handle is rocked in any one of four different positions, the sleeve 18, and the collar 17 move together.

10 One corner of the casing adjacent the collar 17 has a cavity for the reception of a spring tensioned pin or detent 22, which engages in one of the four notches or depressions 23 in one edge of the collar 17, so as to hold it in different adjusted positions, according to the positions to be assumed by the semaphore or signal arm. One of said depressions or notches holds the arm in a suspended position, while another of said 20 notches holds the arm in a downwardly and laterally inclined position, the other holds the arm or semaphore in a horizontal position, or in a laterally and upwardly inclined position. These positions of the arm indicate the intention of the chauffeur driving the machine in front to continue forward, left turn, stop and right turn.

The interior of the sleeve is threaded, said threads 24 being of substantial pitch and 30 are engaged by the threads 25 of the piston 26, which is mounted in the sleeve. This piston has pivoted to one end a link 27, which in turn is pivotally connected at 28 to the lever 11. The link 27 operates through 35 an elongated slot in the bottom of the bifurcation 4. The sides of the elongated slot 29 through which the link 27 engages holds the link from turning, while the length of the slot permits a limited movement of the link.

40 It is obvious that when the handle 19 is rocked from its normal position to a position to permit the spring retained pin to engage the second notch of the collar 17, the sleeve 18 is rotated, causing the piston to 45 move sufficiently to tilt the semaphore or signal arm to indicate left turn.

A further movement of the handle 19 will cause the spring retained pin to engage the 50 third notch, therefore the sleeve will be rotated sufficiently to move the piston, so as to move the semaphore or signal arm to a horizontal position, to indicate stop, whereas a movement of the handle to permit the spring retained pin of the fourth notch of the collar, will cause the semaphore or signal arm to move to a laterally and upwardly inclined position indicating a right turn.

The semaphore or signal arm is hollow, and its front and rear walls are provided 60 with transparent covered openings 30, through which are exposed the indicia bearing strips 31. One end of each strip is wound upon a spring tensioned roller 32. Connected to the other ends of said strips 65 are cords 33, which are wound around the

opposite ends of a roller 34 journaled between the sides of the pivoted ends of the semaphore or signal arm. A cord 35 is wound around the central portion of the roller 34 and also connected thereto, while the other end of said cord 35 is attached at 36 between the bracket and the casing 1. Obviously when the semaphore or signal arm is tilted to any one of the three different positions left, stop or right turn, 75 the indicia bearing elements will be moved so as to be exposed through the transparent covered openings.

An electric lamp 37 is mounted in the semaphore or signal arm, and extending 80 therefrom is a lead 38, which is connected to a contact member 39, which is mounted upon and insulated from the casing 1. This contact member 39 overlies and bears against the collar 17. Another lead 40 connects with the lamp, and is in turn connected to the battery (not shown) which is grounded to the frame of the vehicle. The collar 17 has countersunk in its face a segment of insulating material 41, with which the contact 39 90 normally engages, when the semaphore or signal arm is depending vertically from the casing. However as soon as the handle 19 is moved, thereby moving the collar, the contact 39 engages the collar, and closes the 95 circuit thereby lighting the electric lamp and the semaphore or signal arm, illuminating the interior thereof, whereby the indicia upon the indicia bearing elements are clearly visible at night. The cylindrical reduced 100 end of the casing (which carries the collar 17) has a second reduced portion, on which a cap 42 is threaded, thereby closing the end of the casing. It is obvious that the cap may be removed, in order to supply oil to the 105 interior of the casing, whereby the sleeve and the piston may freely operate.

The invention having been set forth, what is claimed as being useful is:

1. In a semaphore operating mechanism, 110 a casing, a semaphore arm pivoted on the casing, an internally threaded sleeve rotatably mounted in the casing and having an operating handle for effecting rotation thereof, a longitudinally movable piston threaded into the sleeve, a curved link pivotally connected at one end within the casing, a second curved link pivotally connected with the free end of the first named link and with the arm, and a third link pivotally connected with the outer end of said piston and with the intermediate portion of the first named link.

2. In a semaphore operating mechanism, a 115 casing, a semaphore arm pivoted upon one end of the casing, means within the casing for swinging said arm into selected positions, windows in the front and back of the casing, a pair of spring rollers arranged in vertical position within the casing, flexible 120

indicia carrying members secured to and wound upon said rollers and exposed through the respective windows, a triple drum structure at the pivot of the arm, flexible members secured to and wrapped about the outermost drum members and connected with the respective flexible indicia carrying members, and a flexible member secured at one end to the casing and having its other end secured to and wrapped about the intermediate section of said triple drum structure.

3. In a semaphore actuating mechanism, a casing, a semaphore arm pivoted thereon, means for moving the arm, windows in the

front and back of the casing, a pair of spring rollers within the casing, flexible members secured to and wrapped upon said rollers and carrying indicia visible through the respective windows, a pair of drums located 20 at the pivot of the arm, flexible members secured to and wrapped upon said drums and connected with said first named flexible members, and means connected with the drum and the casing for rotating the drum 25 when the casing is swung.

In testimony whereof I hereunto affix my signature.

ARTHUR C. KEPPLER.
